UNITED STATES PATENT OFFICE

171,268

EXPANSIBLE WRIST WATCH BRACELET

John F. Sand, Newark, N. J., assignor to Gemex Company, Union, N. J., a corporation of New Jersey

Application July 31, 1953, Serial No. 26,209

Term of patent 7 years

(Cl. D45—4)

To all whom it may concern:

Be it known that I, John F. Sand, a citizen of the United States and a resident of Newark, Essex County, New Jersey, have invented a new, original, and ornamental Design for an Expansible Wrist Watch Bracelet, of which the following is a specification, reference being had to the accompanying drawing forming part hereof, in which:

Fig. 1 is a top plan of an expansible wrist watch bracelet embodying my new design;

Fig. 2 is a bottom plan view thereof;

Fig. 3 is an edge view thereof;

Fig. 4 is a fragmentary top plan of the bracelet in an expanded condition; and,

Fig. 5 is a fragmentary perspective view thereof drawn on a larger scale.

The dominant features of my design reside in those portions shown in full lines.

I claim:

The ornamental design for an expansible wrist watch bracelet, substantially as shown and described.

JOHN F. SAND.
